UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

GOVERNING MECHANISM FOR STEAM-TURBINES.

1,201,675.

Specification of Letters Patent. Patented Oct. 17, 1916.

Application filed April 28, 1914. Serial No. 834,890.

To all whom it may concern:

Be it known that I, OTTO BANNER, a subject of the German Emperor, residing at Easton, in the county of Northampton and 5 State of Pennsylvania, have invented a certain new and useful Improvement in Governing Mechanism for Steam-Turbines, of which the following is a specification.

This invention relates to fluid operated turbines, and more particularly to turbines adapted to be used through a considerable range of loads.

The object of this invention is to provide a turbine which can be operated at a high average efficiency through a wide range of loads, such a machine being adapted for instance, for use with dynamos or blowing engines driven by a turbine which may at one time be required to run at half normal 20 load or less and at other times at twice or more than twice its normal load. This object and others further to be described are accomplished by the turbine, a practical embodiment of which is shown in the accompanying drawing, in which,

Figure 1 shows a longitudinal section of the turbine, the lower part being in elevation, Fig. 2 shows a plan of the turbine partly in section on the line 2—2 of Fig. 1.

In the drawings the turbine is shown as comprising a horizontally split casing 1, divided by diaphragms or partitions 2, 3, 4, 5 into a high pressure chamber 6, low pressure chambers 7, 8 and 9 and an exhaust chamber 10 which preferably leads by an exhaust conduit 11 to a condenser, (not shown). In the high pressure chamber 6 rotates a high pressure wheel 12 to the blades of which fluid is supplied by a series 30 of nozzles 13, 14, 15 and 16 which lead, respectively, from steam chests 17, 18, 19 and 20. Steam is serially admitted to these steam chests from a high pressure steam conduit 21 by means of valves 22 which are 40 successively opened as the load increases by means of any suitable regulating mechanism, such as shown, for instance, in my previous Patent No. 1,117,306 granted November 17th, 1914, which consists of pistons 23 attached 50 to the valves 22, these pistons being raised and lowered by fluid pressure under the influence of pilot valves 24, these pilot valves 24 being, in turn, raised and lowered by arms 25 on the rock shaft 26 operated from 55 the governor of the turbine.

Under normal operating conditions all the

steam from the exhaust of the high pressure wheel 12 will pass in series through low pressure stage wheels 27, 28, 29 and 30 to the exhaust chamber 10 and thence to the 60 condenser. In such a case high pressure steam would only be passing through nozzles 13 and 14. Under overload conditions high pressure steam will also be admitted by valves 22 to steam chests 19 and 20 and from 65 thence to nozzles 15 and 16. This will cause a large increase in the quantity of steam admitted to the high pressure chamber 6 and as the low pressure wheels 27, 28, etc., are 70 fully or almost fully injected this excess steam cannot pass with sufficient rapidity through the low pressure stages. This will cause the pressure to rise throughout the whole turbine, materially affecting its efficiency.

To take care of the excess steam in the high pressure chamber 6 under overload conditions a low pressure wheel 31 is provided in the exhaust chamber 10 of the turbine. Under normal conditions the blades of this 80 wheel receive no steam and simply revolve in the low pressure of the exhaust chamber. Under overload conditions fluid is supplied to the wheel 31 by groups of nozzles 32 and 33 supplied by conduits 34 and 35 to which 85 steam is admitted from the high pressure chamber 6 by means of valves 36 and 37. Valves 36 and 37 are controlled by pistons 38 similar in construction to piston 23, these 90 pistons being raised and lowered by pilot valves 39 attached to levers 40 which are in turn attached to a rock shaft 41. The rock shaft 41 is connected to rock shaft 26 by arms 42 and 43 and link 44, motion of rock shaft 26 causing a similar motion of rock shaft 41. The opening of the various valves controlling the admission of steam to high pressure wheel 12 and low pressure wheel 31 are so arranged by means, for instance, such 100 as shown in my co-pending application, that under increasing load conditions steam will be admitted first to nozzles 13 and then to nozzles 14. Further increase in load will open the valve 22 and at the same time the valve 36 controlling the admission of fluid from the high pressure chamber 6 to the nozzles 32 supplying low pressure wheel 31. Likewise, when the valve 22 controlling admission to nozzles 16 opens, valve 37 will 105 open admitting a further amount of operating fluid from high pressure chamber 6 to wheel 31. By means of this arrangement,

the additional steam which can be efficiently admitted to the high pressure wheel 12 by opening more nozzles, can be carried off and expanded efficiently in the low pressure wheel 31 thus permitting the low pressure wheels 27 to 30 to receive only a normal amount of steam. As the wheel 31 under normal load conditions is rotated in a vacuum or in low pressure steam, its movement absorbs very little energy when it is not in active operation.

Although the wheel 12 and the wheels 27 to 30 are shown as provided each with a single row of blades, any suitable number 15 of rows of blades and any suitable number of high and low pressure wheels may be provided, the low pressure wheels being of the reaction type, if desired. Likewise, although the low pressure wheel 31 is shown 20 with two rows of blades any suitable number of blades or any number of wheels may be provided. Likewise, any suitable governing mechanism and number of nozzles or nozzle groups may be provided for the high 25 pressure wheel 12 and the low pressure wheel 31, and, if desirable, the admission to the low pressure wheel 31 may be governed by the pressure in the chamber 6 instead of directly by the load.

30 It is to be understood that the present showing and description discloses only one specified modification of the invention, and other forms and modifications are included in the spirit and scope of the invention as 35 expressed in the claims.

I claim—

1. In a fluid operated turbine, a high pressure stage, two low pressure stages, one of said low pressure stages being normally in- 40 active, means for continuously supplying fluid from the discharge of said high pressure stage to one of said low pressure stages, and means for supplying fluid from the discharge of said high pressure stage to said 45 normally inactive low pressure stage only under greater load conditions.

2. In a fluid operated turbine, a high pressure wheel, a series of low pressure wheels continuously receiving steam from said high 50 pressure wheel, a normally inactive low pressure wheel located in the exhaust of said continuously supplied low pressure wheels, and means for supplying steam from the discharge of said high pressure wheel to 55 said normally inactive low pressure wheel under greater load conditions.

3. In combination with a steam turbine comprising a high pressure stage and a series of low pressure stages adapted to receive 60 steam continuously from the discharge of said high pressure stage, a normally inactive low pressure stage, and means governed by the load to supply a greater amount of

live steam to said high pressure stage, and to supply fluid from the discharge of said 65 high pressure stages to said normally inactive low pressure stages under overload conditions.

4. In a fluid operated turbine, a casing having a high pressure chamber, a series of 70 low pressure chambers, and an exhaust chamber, a high pressure wheel in said high pressure chamber, means for supplying steam to said high pressure wheel, low pressure wheels in said low pressure chambers, 75 said low pressure wheels continuously receiving steam from the discharge of said high pressure wheel and discharging said steam into said exhaust chamber, a normally inactive wheel in said exhaust chamber, and 80 means for conveying fluid to said normally inactive wheel from the discharge of said high pressure wheel under greater load conditions.

5. In a fluid operated turbine, a high pres- 85 sure wheel, a series of low pressure wheels having single rows of blades, nozzles for admitting fluid to said high pressure wheel nozzles for admitting fluid from the discharge of said high pressure wheel continu- 90 ously to said low pressure wheels, a normally inactive low pressure wheel having a plurality of rows of blades, and means for admitting fluid from the discharge of the high pressure wheel to said normally inactive 95 wheel under greater load conditions.

6. In a steam turbine, a high pressure wheel, a series of valves for admitting fluid to said high pressure wheel, a low pressure wheel, means for continuously admitting 100 fluid from the discharge of said high pressure wheel to said low pressure wheel, a second low pressure wheel, a conduit leading from the discharge of said high pressure wheel to said second low pressure wheel, a 105 valve controlling said conduit and load governed means for successively opening said high pressure valves and for opening said conduit controlling valve with a late opening high pressure valve.

7. In a steam turbine, a casing, a series of turbine wheels therein, means to pass fluid through said wheels in series, an exhaust chamber receiving the discharge from said wheels, a normally inactive wheel in said 115 exhaust chamber and means to supply fluid from an earlier normally active wheel to said inactive wheel under greater load conditions.

In testimony whereof, I have hereunto set 120 my hand.

OTTO BANNER.
